CLEANER SILENCER UNIT

Wesley W. McMullen, Flint, Mich., assignor to General Motors Corporation, Detroit, Mich., a corporation of Delaware

Application November 16, 1953, Serial No. 392,338

6 Claims. (Cl. 183—15)

This invention relates to cleaner silencer units for engines and other devices having air induction means and has particular relation to a unitary cleaner silencer structure for automotive and other uses.

One form of cleaner silencer structure which heretofore has been widely used for automotive and other purposes is a structure which is assembled from various cleaner and silencer units. The units employed have been more or less standard units which could be used in assembling any number of different cleaner silencer structures of various sizes and capacities. While this method of constructing cleaner silencer structures made possible the production of a relatively large number of different devices with limited tools and equipment, it did not provide the best and most economical device for any specific application.

It is now proposed to provide an inexpensive cleaner silencer structure in which the various parts are particularly designed to provide the most efficient device for the space available, which can be made from a relatively small number of parts, which can be serviced readily, which does not include gaskets of any kind, and which can be serviced when required without disassembling the greater part of the structure.

In the drawing:

Figure 1 is a side elevational view with parts thereof broken away, and illustrated in cross section and illustrating a cleaner silencer unit structure embracing the principles of the invention.

Figure 2 is an upper plan view of the structure disclosed by Figure 1 with parts thereof broken away to better illustrate the interior of the upper part of the structure.

The cleaner silencer structure 10 comprises a main unitary outer casing 11 which is formed to provide a unitary closure element for a cleaner element 12 and a silencer element 13.

The cleaner element 12 comprises a closure or casing 14 having a continuous side wall 16 and a bottom or lower wall 17. The bottom wall 17 is formed to provide a closed upwardly extending central part 18 surrounded by a downwardly extending annular part 19. The space within the casing 14 is adapted to be filled entirely with filtering means or material to provide a filter element 21 of any suitable type. The filtering means or material is formed to extend entirely across the chamber formed by the casing 14 from within the side wall 16 and to entirely cover the bottom wall 17. In the present instance it is proposed to form the filter element 21 of filtering material which has been pressed or molded to substantially fit the shape of the interior of the casing 14.

The annular part 19 of the wall 17 is adapted to be radially and circumferentially slotted in such manner that spacing members 22 may be bent downwardly from the annular part 19 to provide spaced and annularly disposed inlet openings such as that indicated at 23. The openings 23 provide the only air inlet means extending through the casing 14 for the admission of air to be cleaned by

2

the filter element 21. Surrounding the lower part of the casing 14 is an inlet closure or casing 24 which is formed by a continuous side wall 26 and a closed lower or bottom wall 27. The side wall 26 may be uniformly spaced from the side wall 16 to provide an annular inlet passage 28 leading to the lower part of the cleaner casing 16 and to the inlet opening means 23. The lower wall 27 has an outwardly depressed annular part 29 and an upwardly and inwardly depressed central part 31. The part 31 is adapted to extend within but in spaced relation to the part 18 of the wall 17 of the cleaner casing 14. The outwardly depressed part 29 of the lower wall 27 is spaced below the lower extremity of the spacing means or supports 22 and provides an oil chamber or sump indicated at 32. The oil chamber or sump 32 is adapted to be filled with oil during the operation of the device to the level indicated at 33.

The central part 31 extends upwardly within the wall 17 to a height exceeding the oil level 33.

Between the lower walls 17 and 27 is an oil control baffle 34 for the cleaner 12. The baffle 34 may be formed to provide an upwardly depressed part 36 which may fit the exterior surface of the upwardly depressed part 18 of the wall 17. Beneath the inlet openings 23 the outer part of the baffle 34 may slope downwardly toward the outer extremities of the openings 23 and then upwardly where the outer peripheral edge of the baffle approaches the wall 26. The outer ends of the supports 22 are adapted to engage and to rest upon the baffle 34. The wall 26 may be formed to provide ribs 37 for engaging and supporting the outer peripheral edge of the baffle for compressing the baffle against the supports 22 and the outer surface of the part 18 of the wall 17. The space between the ribs 37 and the clearance between the edge of the baffle 34 and the wall 26 provides passage means through which the oil may circulate from the under to the upper side of the baffle during operation of the cleaner. The inlet casing 24 may be held in position around the cleaner casing 14 by fastening means such as the bolt and wing nut device indicated at 38. The head of the bolt may engage the inner surface of the wall 17 and the bolt may extend through and be staked within aligned openings in the walls 17 and 27 and the baffle 34 so that when the wing nut is tightened the casings 14 and 24 will be secured together in such a way as to stress the baffle 34 between the ribs 37, the lower ends of the spacing members 22 and the outer surface of the part 18 of the wall 17.

It will be apparent that when the wing nut is removed the inlet casing 24 may be entirely removed from the casing 14 and the baffle 34 so that the casing may be cleaned and new oil may be supplied to fill the sump 32.

The upper wall 39 forming a cover for the cleaner 12 may be generally arcuate in formation to provide an outlet chamber 41 about the filter element 21 and the casing 14. The space above the upper wall may be enclosed by a cylindrical wall or sleeve indicated at 42. The adjacent edges of the walls 16, 39 and 42 may be flanged outwardly at 43 to provide means for securing the walls together. Between the peripheral flanges on the walls 39 and 16 it may be considered desirable to provide a screen 44 which may extend inwardly over the filter element 21 for securing the filter element within the casing 14. The flanges on the walls 42, 39 and 16 and the outer edge of the ring 44 may be secured together by a bead 46 which in the present instance is formed by extending the flange of one of the walls around the edges of the remaining flanges and the ring.

It will be apparent that the bead 46 will secure the cleaner 12 to the wall 42 of the silencer element 10 so that the cleaner and silencer cannot be disassembled after

the structure is manufactured. The filter element 21 likewise cannot be removed from the casing 14 although the filter element may be cleaned by removing the casing 24 and immersing the cleaner 12 in any suitable cleaning fluid.

In order to form a suitable resonating chamber in the silencer 10 for silencing noise that may originate within the device with which the structure is used, it is proposed to depress the wall 39 upwardly within the space within the wall 42 in such manner as to enlarge the chamber 41 and to provide an obliquely disposed wall indicated at 47. The wall 47 may be flanged outwardly at 48 to provide an opening leading from the chamber 41 above the cleaning element 21. A straight tube 49 also disposed obliquely within the silencer 13 and in normal relation to the wall 47 may be welded or otherwise secured within in the flange 48 to elongate and to extend the passage leading from the chamber 41.

The upper end of the silencer 13 may be formed by a closure, cap, cover or end casing indicated at 51. The end casing 51 may be formed by an upper wall 52 and a lower wall 53, the upper wall being formed to provide a continuous side wall 54 extending laterally toward the lower wall 53 and being provided with a flange 56 around the edge thereof and adapted to be bent around the peripheral edge of the lower wall 53 to provide a bead 57 securing the two walls rigidly together.

The end casing 51 may be elongated in formation as is shown by Figures 1 and 2 and may be provided adjacent one end thereof with a relatively large opening surrounded by a flange 58 formed in the lower wall 53. The flange 58 is adapted to be disposed in telescopic relation to the upper end of the wall 42 so that the two may be secured together to close the upper end of the silencer chamber. With such construction it will be apparent that the end casing 51 has a part extending laterally from the upper end of the structure to provide an elongated and relatively wide outlet which may be connected to the induction system of an engine or any other device.

The end of the casing 51 opposite the flange 58 may be flanged as indicated at 59 to form an outlet passage 60 and may be slotted around the flange 59 as indicated at 61 to provide means for connecting the structure to the induction passage of any device with which the structure may be used. Attaching means such as that indicated at 62 may extend around the flange 59 for tightening the flange around the induction means.

The end of the casing 51 opposite the flange 58 may be provided with an inner liner indicated at 63. The inner liner is formed in such a way as to substantially fit the inside surface of the casing 51 opposite the flange 58 and to extend within the flange 58 except that the side of the inner liner across the part of the casing leading to the outlet from the structure may be formed to provide an obliquely disposed wall 64. The wall 64 is considerably spaced from the obliquely disposed wall 47 and may extend substantially in parallel relation thereto.

It is proposed to secure the end casing 51 permanently and rigidly to the upper end of the side wall 11 in any suitable manner as by spot welding at 66 through the lower ends of the inner liner 63, the flange 58 and the upper end of the wall 42. When the end casing 51 is so secured to the wall 11, it will be apparent that all of the cleaner silencer structure except the inlet casing 24 will comprise an integrally manufactured unit.

In the present instance it is proposed to form the silencer 13 by forming within the end casing 51, the wall 42 and the wall 39 a resonating chamber 67 which may be tuned in such a way as to attenuate the sound waves moving outwardly in the air flowing through the structure to the induction means. The resonating chamber 67 may be connected to the outlet passage leading from the silencer by any suitable means such as a tube 68 surrounding the outer end of the tube 49 and secured

in spaced relation thereto within a flange 69 formed around an opening in the wall 64.

The silencer 13 also may be provided with sound absorbing means 71 which may be secured against the inside surface of an obliquely disposed part 72 of the side wall 54 of the casing 51 and immediately adjacent the outlet passage 60 leading from the structure. The slope of the wall part 72 is made in such a way as to direct the air flowing through the structure downwardly into the outlet passage 60. The sound absorbing means 71 may be constructed in any suitable manner as by providing a fibrous body of sound absorbing material 74 within a perforated wall 76 extending across the end of the casing 54. The wall 76 may be provided with flanged ends 77 which may be welded or otherwise secured to the side wall 54 as is indicated at 78. The sound absorbing material 74 may be employed to absorb high pitch, hissing sounds that may emanate from the induction means through the outlet opening passage 60.

20 It will be apparent that the structure 10 is largely formed from a relatively small number of parts secured together in such a way as to constitute a single unit. The only parts which require removal in order to service the structure is the casing 24.

25 I claim:

1. A cleaner silencer unit comprising a casing having a cover, said cover being formed at one side to provide a flange telescopically engaging another part of said casing, said cover being formed at the side thereof opposite said

30 flange to provide an outlet opening adapted to be connected to an air induction means, an inner lining for said cover and having an edge extending within said flange and a wall extending obliquely across said cover between said flange and said outlet opening, means securing said cover and said inner lining to said other part of said casing at said flange, a passage formed in said obliquely disposed wall and providing communication between said casing and said outlet, and cleaner and silencer means within said casing.

40 2. An air cleaner structure comprising a casing forming a chamber and having an upper wall, a lower wall and a continuous side wall, said upper wall being formed to provide an outlet from said chamber within said casing, filter means within said chamber and extending entirely across the central part of said chamber and filling the lower part of said chamber and terminating in spaced relation to the upper wall of said casing, annularly disposed inlet opening means formed in the lower wall of said casing adjacent the side wall of said casing and in spaced relation to the central part of said casing, an inlet

45 casing having a lower wall and a side wall and receiving the lower end of the side wall of said casing and being spaced from the side wall and lower wall of said cleaner casing to provide an inlet extending around said cleaner casing and leading to said inlet opening means, and means disposed externally of the central part of said cleaner element for securing said lower wall of said inlet casing to the lower wall of said cleaner casing at the central part of said air cleaner structure.

50 3. An air cleaner structure comprising a cleaner casing having an upper wall, a lower wall and a continuous side wall, said upper wall having an outlet opening for discharging air from said cleaner structure and said lower wall extending entirely across the central part of said cleaner casing and having annularly arranged inlet opening means formed adjacent said side wall and in remote

55 relation to the central part of said lower wall, air cleaning filter means within said cleaner casing and extending across the central part of said casing, an air cleaner baffle extending across said lower wall and beneath said inlet opening means and having a peripheral edge extending beyond said inlet opening means, an inlet casing having a side wall and a lower wall and being adapted to receive said cleaner casing and said baffle, said side wall of said inlet casing being spaced from said side wall

of said cleaner casing to provide an annular inlet leading to said inlet opening means, said lower cleaner casing wall below said inlet opening means and said baffle being formed to provide an oil sump, said inlet casing being formed to provide abutment means engaging said peripheral edge of said baffle and said baffle being formed to engage the central part of the lower wall of said cleaner casing, and means disposed externally of the central part of said cleaner element for detachably securing said lower wall of said cleaner casing to said lower wall of said inlet casing.

4. An air cleaner comprising a casing having an upper wall, a lower wall and a continuous side wall and being formed to provide therein a cleaner chamber, a cleaner outlet formed in said upper wall, a cleaner inlet formed in said lower wall around the central part of said lower wall and adjacent the lower edge of said side wall, said lower wall being depressed inwardly at the central part thereof and within said cleaner inlet means to provide for closing said cleaner chamber to the atmosphere except through said inlet opening means, a baffle having the central portion thereof formed to fit said depression in said lower wall and having a peripheral portion extending below and in spaced relation to said inlet opening means, means extending between the outer peripheral part of said lower wall of said casing and the outer peripheral part of said baffle for uniformly spacing said parts of said lower wall and baffle, an inlet casing having a side wall and a bottom wall, said bottom wall having a centrally disposed depression formed therein and extending within but in spaced relation to said depressions in said baffle and said lower wall of said casing, said lower wall of said casing being formed at the outer peripheral part thereof to provide an annular oil supply chamber extending beneath said inlet opening means and said baffle, said side wall of said inlet casing being spaced from the side wall of said cleaner casing to provide an annular inlet opening leading to said inlet opening means between said baffle and said cleaner casing, means formed on the outer peripheral edge of said baffle and said inlet casing side wall for supporting said baffle, and fastening means for removably securing said inlet casing to said cleaner casing and for clamping said baffle between said inlet casing and said cleaner casing, said fastening means being accessible from beneath the central part of the lower wall of said inlet casing and being adapted to secure the central parts of said lower wall of said inlet casing, said baffle and said bottom wall of said cleaner casing in fixed relation.

5. An air cleaner structure comprising a cleaner casing having an upper wall and a lower wall and a continuous side wall, said upper wall having an outlet formed therein for discharging air from said cleaner structure, said lower wall having annularly arranged inlet opening means formed adjacent said side wall and in remote relation to the central part of said lower wall for supplying air to the interior of said cleaner casing, filter means within said cleaner casing for cleaning said air, a baffle extending across said lower wall and beneath said inlet opening means and having a peripheral edge extending beyond said inlet opening means, an inlet casing having a side wall and a lower wall and being adapted to receive said cleaner casing and said baffle, said side wall of said inlet casing being spaced from said side wall of said cleaner casing to provide an annular inlet leading to said inlet opening means, an oil sump formed in said inlet casing below said inlet opening means, annular abutment means

formed around said lower wall of said inlet casing and at the outer extremity of said oil sump and between said annular inlet and said inlet opening means for supporting said peripheral edge of said baffle, spacer means projecting from said lower wall of said cleaner casing and adjacent said inlet opening means and within said peripheral edge of said baffle and disposed to engage and to support said baffle inwardly of said peripheral edge, said filter means and said lower wall of said cleaner casing and said baffle and said lower wall of said inlet casing being formed to extend entirely across the lower part of said cleaner casing with the central part of said lower wall of said cleaner casing projecting into the lower central part of said filter element and with the central part of said baffle projecting into and substantially fitting the exterior surface of said central part of said lower wall of said cleaner casing and with the central part of said lower wall of said inlet casing projecting into but in spaced relation to said central part of said baffle, said filter element in said casing being formed to provide an annular part extending downwardly in said cleaner casing around said central parts of said lower wall of said cleaner casing and said baffle and said lower wall of said inlet casing and into the vicinity of said inlet opening means and being formed above said central parts to extend continuously and entirely across said cleaner casing, and fastening means engaging said central parts of said walls and said baffle for securing said inlet casing to said cleaner casing and for clamping said baffle between said abutment and said spacer means and within said central part of said lower wall of said cleaner casing.

6. A cleaner silencer unit comprising an elongated cylindrical casing having an outlet extending laterally from one side and at one end thereof and adapted to be secured to air induction means, a wall extending transversely across said casing and dividing said casing into a cleaner chamber and a silencer chamber, air cleaning means associated with said cleaner chamber, outlet passage means formed in said wall and leading from said cleaner chamber to said casing outlet and providing acoustical coupling means between said casing outlet and said silencer chamber, said casing being formed on opposite sides of said wall by wall sections secured against opposite surfaces at the edges of said wall by a seam, said cleaner chamber wall section being disposed substantially concentrically with respect to said silencer chamber wall section but radially inwardly with respect to said silencer chamber wall section, and a cleaner inlet casing secured to the lower part of said casing and having an annular side wall disposed outwardly of said cleaner chamber wall section and substantially in alignment with the outer edge of said seam and providing an air inlet leading to the lower part of said cleaner casing.
